APPARATUS FOR NOTCHING CAN BODY
BLANKS

Ed Laxo, Oakland, Calif., assignor to Atlas Imperial Diesel Engine Co., Oakland, Calif., a corporation of Delaware

Application April 29, 1947, Serial No. 744,681

2 Claims. (Cl. 164—50)

1

The present invention pertains to can body making apparatus, and is more particularly directed to apparatus for performing certain metal working operations on body blanks preparatory to their forming into a side seamed cylindrical body member.

In the formation of can bodies, the corners of the body blanks are notched and slit preparatory to bending the oppositely arranged side edges into hooks, which are interlocked after the blank is formed into cylindrical shape on the forming mandrel of the body making equipment. Heretofore, the punches for notching and slitting the blanks have been mounted on a slide capable of reciprocating in a guide to and from a cooperating die. Such slide necessarily overhung the supporting guide by a considerable extent in view of the need for the guide ways to clear the side edges of the blanks.

Since such punch and die equipment operates at a relatively high speed (often in excess of 400 body blanks per minute), the slide must have a relatively loose fit in the guide ways for proper running clearance. As a consequence, it is practically impossible to maintain the punches and dies in proper adjustment, resulting in the formation of corner notch contours and slit lengths which vary among the can blanks and even between adjacent can blanks passing through the machine. Moreover, the excessive play of the slide in the ways makes it difficult for the corners of the body blanks to be cut cleanly. It is readily apparent that the shearing edges of the punches and dies are difficult to arrange accurately with respect to each other in view of the necessity for allowing for the play in the parts; otherwise, there is the hazard of dulling or breaking the cutting parts after operating upon only a relatively few blanks. The net result of the looseness of the slide in the ways is to dull the punches and dies prematurely, forming burred corners of improper configuration in the blanks, rendering it difficult to produce a tight can body seam, and sometimes causing the apparatus to jam.

Accordingly, it is an object of the present invention to provide a machine for operating on can body blanks, the punches and dies of such machine being supported accurately with respect to each other, the punch being movable along a predetermined path by a mounting member operating with substantially no looseness on its cooperable support.

A further object of the invention is to provide a metal working machine whose punch and die are supported and relatively moved in such man-

2

ner as to provide clean cut or formed can body blank corners of accurate contour and dimensions.

Another object of the invention is to provide for the ready assembly and adjustability of a can body blank punch on a supporting and operating member.

Yet another object of the invention is to provide an improved manner of securely holding a can body blank die on the frame of the forming or notching machine.

Still another object of the invention is to provide a machine for forming can bodies, said machine having an improved manner of rigidly securing a punch to its mounting and operating member.

One form which the invention may assume is exemplified in the following description and illustrated by way of example in the accompanying drawings, in which:

Fig. 1 is a cross-section through the notching station of a can body making machine, parts of the machine being omitted for the purpose of clarity.

Fig. 2 is a top plan view of part of the punch mechanism at the left side of the machine as viewed in Fig. 1.

Fig. 3 is a partial section taken along the line 3—3 on Fig. 1, disclosing the manner of clamping a punch to its holder.

Fig. 4 is a partial plan view of the die block and bed of the machine as seen generally along the line 4—4 on Fig. 1.

The apparatus disclosed in the drawings constitutes the mechanism for notching and slitting the corners of can body blanks B, which may have other operations performed upon them prior to their feeding to the notching station of the body maker. The grain of the body metal may first be broken to make the blanks more amenable to formation into a cylindrical container, and the blanks may then be fed to a blanking or impression station (not shown) wherein provision is made for performing certain operations prior to delivering the blanks to the notching tools. For example, the corners of the body blank may be bent slightly so that it will more closely follow the curvature of a mandrel about which the blank is subsequently formed, and allow the finished side seam to be provided with a relatively thin lap requiring a minimum of solder and having a greater holding strength.

The body blanks are fed from the blanking or impression station to the notching station by opposed, parallel feed bars 10 having the usual

fingers (not shown) for engaging the rear edge of a body blank and moving it intermittently and in proper timed sequence from station to station along the length of the body making machine. These feed bars are slidably mounted on opposed side frames 11 of the apparatus, which may be adjustably mounted on the base 12 of the machine to and from one another for the purpose of accommodating body blanks of different widths designed to provide cylindrical can bodies of various diameters. Since this feature forms no part of the present invention, the details are not disclosed herein.

Inasmuch as the mechanisms on the side frame 11 are virtual duplicates of each other, although oppositely arranged, a detailed description of one side of the machine will suffice for both sides.

Each side frame 11 has a bed portion 13 on which the feed bar 10 is adapted to slide. It also is provided with an inner side member 14 secured thereto in any suitable manner, as by means of cap screws 15, and having an inwardly extending shoulder 16 on which a plate 17 is mounted, which plate extends across the machine and also rests upon the shoulder 16 on the opposite side, the plate being secured to the shoulders by countersunk screws 18 or the like, with its top surface 17a lying in the same plane as the upper surface 10a of the feed bars 10. The inner member 14 has an intermediate outwardly projecting, longitudinally extending tongue 19 engageable within a companion groove 20 in the feed bar. Mounted on the side frame 11 adjacent the feed bar is a longitudinally extending die block 21 resting within a channel shaped groove 22 in the frame, and engaging the base 23 and outer side surface 24 of the groove. In effect, the die block 21 and inner member 14 form guide ways for preventing lateral movement of the feed bar 10.

The die block 21 is held in snug engagement with the bottom 23 and outer side 24 of the channel 22 by one or more diagonal screws 25, each extending through an enlarged diagonal bore 26 in the side frame 11 into threaded engagement with a threaded diagonal hole 27 in the die block. Tightening of the screw 25 so as to engage its head 28, or intervening washer 29, with the inclined outer surface 30 of the side frame draws the die block 21 downwardly and outwardly in the channel, in order to position the outer surface 21a of the die block snugly against the companion outer surface 24 of the channel and its bottom surface 21b snugly against the bottom 23 of the channel. Any necessity for the die block 21 to shift during tightening of the screw 25 is permitted since the screw may shift laterally of its axis within the enlarged bore 26. Longitudinal movement of the die block 21 along the channel 22 is prevented by countersunk screws 31 passing through the end portion of the block and into the side member 11, provision being made, of course, by any suitable means (not shown) well known in the art to allow transverse movement of the die block 21 when screw 25 is tightened.

The upper surface 21c of each die block lies in the same plane as the upper surfaces 10a, 17a of the plate and feed bar in order to support the body blank B in plane fashion and without distortion thereon. Each die block 21 has a pair of oppositely arranged, longitudinally spaced die cavities 32 for the reception of cooperable punches 33 designed to notch or slit the corners

of a body blank placed in appropriate registry with respect to the cavities by a registering mechanism (not shown). It is to be understood that the cavities 32 in the die block on one side of the machine may be different from the cavities in the die block on the other side of the machine, since different configurations and operations on the corners of the body blank are to be made on one side of the blank than on the other side of the blank. In general, the blank corners on one side of the machine, as the left of the machine as seen in Fig. 1, may be notched, whereas the corners on the other side of the machine may be slit.

During the feeding and registering of the body blanks along and at the notching station, their side edges are appropriately guided and supported by guide plates 34 suitably secured to the dies 21, as by cap screws 35 or the like. These guide plates are notched so as to avoid interference with the punches 33 as they move into and out of the die block cavities 32.

One punch is provided for each cavity, and it is adjustably mounted in a punch holder 36 which is clamped to a rocking lever 37 oscillatable upon a shaft 38 fixed to and extending between bearings 39 at the upper ends of supporting uprights 40 secured to the side frame 11 of the machine. Needle or other suitable anti-friction bearing elements 41 are interposed between the shaft 38 and lever 37 to insure free pivotal movement of the latter. The outer end of the rocking lever 37 is adapted to receive a stud or pin 42 suitably clamped thereto. As disclosed in the drawings, the outer arm of the rocking lever is split to provide spaced ears or lugs 43 adapted to be moved toward each other by a cap screw 44 extending through one ear and threaded into the other ear, which action clamps the split end of the arm around the stud 42. The stud extends outwardly of one face of the rocking lever and has one end of a connecting rod 45 mounted thereon through the intermediary of needle bearings 46, or other suitable anti-friction bearings. Endwise movement of the connecting rod from the stud or pin is prevented by a retainer cap 47 engaging the end face of the connecting rod 45 and suitably secured in position by a cap screw 48 threaded into the pin with its head engaging the exterior of the cap.

The connecting rod 45 depends from the rocking lever 37, its other end being formed as a strap 49 encompassing an eccentric 50 secured to a drive shaft 51 rotatable at the proper rate of speed by a suitable electric motor and intervening gearing (not shown). It is to be understood that there is a drive shaft and connecting rod mechanism on each side of the machine and that such members move in unison to effect simultaneous movement of the punches 33 toward and away from the cooperable dies 21 to effect simultaneous notching and slitting of the body blank corners.

Each punch 33 of the pair of punches at each side of the apparatus is mounted for individual adjustment on its holder 36, which has a generally vertically extending slot or groove 52 in which the punch is snugly received, the upper end of the punch being adapted to bear against a set screw 53 extending through an inwardly projecting top wall 54 of the holder, which screw may be locked in any selected adjusted position by a nut 55 threaded thereon and adapted to bear against the upper surface of the top wall. When the set screw 53 has been appropriately threaded into

the top wall, in order to properly position the lower end of the punch 33 with respect to the die block 21, the punch may be clamped in such adjusted position by a plate 56 engaging its surface and held snugly thereagainst to hold the punch firmly against the base of the groove 52 by a plurality of cap screws 57 extending through the plate 56 and threaded into the holder 36.

There is one punch holder 36 for each punch 33 and this punch holder is adjustably mounted in the inner arm of the rocking lever 37 to permit longitudinal movement of the punch longitudinally of the die block for accurately locating the punch in alignment with the die cavity. Specifically, the punch holder has a flat rear face 58 adapted to engage a companion backing face 59 formed in the rocking lever. The punch holder also has a downwardly and outwardly inclined lower surface 60 adapted to cooperate with a companion inclined surface 61 formed on the upper side of a ledge 62 projecting from the rocking lever inwardly beyond its backing face 59. In effect, the side 61 of the ledge and backing face 59 form an acute angle with respect to each other, or a V-shaped groove into which the corresponding lower V-shaped portion of the punch holder 36 is receivable.

The upper end of each punch holder is also provided with an upper surface 63 diverging with respect to its lower surface 60, that is, such upper surface is inclined upwardly and outwardly to form an acute angle with its outer face 58. A cap piece 64 is adapted to be clamped to the upper end of the rocking lever 37 and against the upper portion of the punch holder 36 by a screw 65 extending through the cap piece. This cap piece has an inner projecting ledge 66 providing a tapered face 67 companion to the punch holder face 63 and also a short depending leg 68 adapted to be received within an L-shaped notch 69 at the outer upper corner of the rocking lever 37; the inner surface of the leg 68 shouldering against the adjacent surface of the notch 69.

It is apparent that tightening of the cap screws 65 moves the cap 64 downwardly toward the rocking lever 37, and in so doing forces the lower inclined surface 60 of the punch holder 36 down along the companion surface 61 of the projecting ledge 62 and the upper tapered surface 67 of the cap 64 down along the upper tapered surface 63 of the holder, all of which forces the holder 36 snugly against the backing face 59 of the rocking lever and effects its secure clamping to such lever. The punch holder 36 may be adjusted longitudinally along the rocking lever 37 in order to locate the punch 33 accurately in alignment with the die cavity prior to securing of the cap piece 64 in place and the firm gripping of the punch holder between the backing face 59, ledge 62 and tapered portion 66 of the cap piece.

As stated above, there is a separate punch holder 36 for each punch and also a separate clamp piece 64 for each holder, in order that the parts may be appropriately adjusted and held securely in such adjusted position.

As the drive shafts 51 on both sides of the machine rotate in synchronism with one another, the rocking levers 37 are oscillated on their supporting shafts 38 and the punches 33 on both sides of the machine are moved at the proper time into and out of the die cavities 32, effecting accurate notching of the corners of the body blanks B as they are fed to the notching station and appropriately registered therewith by the registering mechanism described in my above identified ap-

plication, or by any other suitable registering mechanism. The mechanism may be operated at relatively high speed without any necessity for providing for play in the parts. Since there is an absence of rectilinearly moving members, there is no need for providing excessive operating clearance, as is essential in connection with reciprocating slide and guide way devices. All that is required is to provide the normal close bearing clearance between the shaft 38 and the anti-friction bearing 41, which produces very little, if any, deviation of the punches 33 from their intended path of movement with respect to the die block cavities 32. As a result, notching and slitting is performed accurately and consistently as the body blanks are fed through the machine.

It is also to be noted that despite the relatively great overhang between the rocking lever support 38 and the punch 33, the parts are all of substantial dimensions and extremely rigid, introducing no deflection which might otherwise impair accurate functioning of the mechanism. Moreover, a simple and effective means has been provided for quickly and accurately adjusting the punches 33 with respect to the punch holder 36 and the punch holder with respect to the supporting lever 37. In addition, a simple manner of appropriately adjusting the die blocks 21 through the simple expedient of the diagonally arranged screws 25 has been provided, all of which contributes to the production of a clean shearing action of the body metal as the punches engage its upper surface and are forced therethrough into the die block cavities.

The horizontal axes of the rocking lever shafts are positioned a slight distance y above the plane of the surface 21c of the die blocks. Such distance may be equal to the thickness of the body blank B in order that the punches 33 be moved downwardly in an arc with their lower ends engaging the metal and then swinging in a direction away from or outwardly of the inner shearing edge of the die, in effect, drawing the punches 33 away from the die 21 as they pass this shearing edge and making it unnecessary to undercut the face of the die below such shearing edge to provide clearance for movement of the punch within the die cavity. This provides for a much stronger shearing edge on the die as compared with the acute angle edge which undercutting would produce.

While the invention has been described with specific reference to the notching and slitting of the corners of can body blanks, it is to be understood that it is applicable to mechanisms performing other forming operations on the body blanks, as, for example, in connection with the operation at the blanking or impressing station immediately preceding the notching station, or at the folding station for forming the body hooks immediately following the notching operation. The punches and dies would be similarly mounted, as specifically described herein in connection with the notching and slitting operations, and the punches would be rocked or oscillated to and from the cooperable forming dies in substantially the same manner as described herein.

It is, accordingly, apparent that a can body blank machine has been provided in which the punches and dies may be rigidly and accurately supported, with provision being made for their movement with a minimum of play to and from one another in effecting the required operations on the body blanks. When specifically applied to the notching station, assurance is had that

clean cut body blank corners of accurate contour and dimensions will be provided. The mechanism is readily adjustable to permit operations upon a variety of body blank sizes.

While I have shown the preferred form of my invention, it is to be understood that various changes may be made in its construction by those skilled in the art without departing from the scope of the invention as defined in the appended claims.

Having thus described my invention, what I claim and desire to secure by Letters Patent is:

1. An apparatus for forming can bodies including a frame, a stationary die member supported on the frame with its upper working surface disposed in a horizontal plane, an oscillatory lever mounted on the frame to oscillate about a horizontal axis so as to move one end thereof in a vertical plane toward and away from the horizontal working surface of the stationary die member, said end of the lever being formed with a flat backing face disposed in a plane parallel to the axis about which the lever oscillates and substantially perpendicular to the working face of the stationary die member at the time the punch engages one of said bodies, an upwardly and outwardly inclined projecting ledge extending along the lower terminus of the backing face on said lever, a punch holder having a flat surface to seat against the flat backing face and having a downwardly and inwardly inclined lower surface complementary to said ledge and an upper surface tapered upwardly and inwardly, a clamp mounted on the lever at the upper terminus of the backing face and formed with a tapered surface complementary to the tapered upper surface of the punch holder, screw means engaging the clamp and the lever to fix the clamp to the lever in a manner clamping the punch holder against the flat backing surface and between the ledge and the clamp, a punch secured to the punch holder, and means for oscillating said lever to move said punch toward and away from the working surface of the die member.

2. An apparatus for forming can bodies including a frame, a stationary die member supported on the frame with its upper working surface disposed in a horizontal plane, an oscillatory lever mounted on the frame to oscillate about a horizontal axis so as to move one end thereof in a vertical plane toward and away from the horizontal working surface of the stationary die member, said end of the lever being formed with a flat backing face disposed in a plane parallel to the axis about which the lever oscillates and substantially perpendicular to the working face of the stationary die member at the time the punch engages one of said bodies,

an upwardly and outwardly inclined projecting ledge extending along the lower terminus of the backing face on said lever, a punch holder having a flat surface to seat against the flat backing face and having a downwardly and inwardly inclined lower surface complementary to said ledge and an upper surface tapered upwardly and inwardly, a clamp mounted on the lever at the upper terminus of the backing face and formed with a tapered surface complementary to the tapered upper surface of the punch holder, screw means engaging the clamp and the lever to fix the clamp to the lever in a manner clamping the punch holder against the flat backing surface and between the ledge and the clamp, said punch holder having a recess formed therein extending inwardly from the face of the punch holder opposite the face thereof engaging the flat backing face with the inner face of the recess parallel to said flat backing face, a punch member fitting said recess, means securing the punch member in said recess but operable to permit adjustment of the punch member in said recess in a direction parallel to the plane of said backing surface, said punch holder having a fixed rigid portion overlying said recess and the punch member therein at the upper end thereof, an adjustment screw threaded through said fixed portion and capable of adjustment coaxially of the punch member to adjust its position along said recess, and means for oscillating said lever to move said punch member toward and away from the working face of the die member for performance of an operation on a can body blank placed upon said die member.
